UNITED STATES PATENT OFFICE

JAMES T. ATWOOD, OF ROCKFORD, ILLINOIS

DESIGN FOR AN OUTER MEMBER OF A COVERED JOINT HINGE

Application filed November 2, 1931. Serial No. 41,595. Term of patent 14 years.

To all whom it may concern:

Be it known that I, JAMES T. ATWOOD, a citizen of the United States, residing at Rockford, in the county of Winnebago and State of Illinois, have invented a new, original, and ornamental Design for the Outer Member of a Covered Joint Hinge, of which the following is a specification, reference being had to the accompanying drawing, forming part thereof.

In the drawing—

Figure 1 is a front view; Fig. 2 is a side view; Fig. 3 a top view, and Fig. 4 a perspective view of the outer member of a covered joint hinge showing my new design.

I claim:

The ornamental design for the outer member of a covered joint hinge as shown.

JAMES T. ATWOOD.
